UNITED STATES PATENT OFFICE

1,958,960

HYDRAULIC LIFT

William H. Warner, Ottawa, Kans.

Application February 10, 1934, Serial No. 710,701

7 Claims. (Cl. 254—93)

This invention relates to automobile lifts of the hydraulic type, the primary object of the invention being to provide a lift comprising a pair of cylinders, in which vertically movable pistons 5 operate under hydraulic pressure, the construction of the cylinders being such that one cylinder constitutes a tank containing fluid to be forced into the adjacent cylinder, operating the piston movable therein.

10 An important object of the invention is the provision of a hydraulic lift wherein a pair of lifting pistons are employed, the operating means being such that the movement of one piston is governed by the movement of the adjacent 15 piston, thereby insuring the pistons moving evenly and in unison.

With the foregoing and other objects in view, which will appear as the description proceeds the invention resides in the combination and arrangement of parts and in the details of construction hereinafter described and claimed, it being understood that changes in the precise embodiment of the invention herein disclosed, may be made within the scope of what is claimed, 25 without departing from the spirit of the invention.

Referring to the drawings:

Figure 1 is a longitudinal sectional view through a lift constructed in accordance with 30 the invention.

Figure 2 is a sectional view taken on line 2—2 of Figure 1.

Figure 3 is a sectional view taken on line 3—3 of Figure 1.

35 Figure 4 is an enlarged sectional view illustrating the vent port and construction of the upper portion of the cylinders.

Figure 5 is a sectional view taken on line 5—5 of Figure 1.

40 Referring to the drawings in detail, the reference character 5 designates one of the cylinders of the lift, and the reference character 6 designates the other cylinder of the lift, the cylinders being in communication with each other, through 45 the pipe 7, which is disposed near the lower ends of the cylinders.

Secured within the upper end of the cylinder 5, is an elongated bearing 8, which is held in position, by means of the rods 9, that have their upper 50 ends threaded to receive the nuts 10. This bearing member 8 is formed with cut out portions 11 and 12 respectively, which cut out portions are in communication with each other, through the passageways 13 at their lower ends, and through 55 ports 13' at their upper ends. Openings 14' are

also formed at the lower end of the bearing 8, providing communication between the space formed by the cut out portion 12, and cylinder 5, for venting purposes.

At the upper end of cylinder 6, is a bearing 60 member 14, which bearing member also has cut out portions 15 and 16 that communicate through the port 17, the port 17 being formed at the lower end of the vent opening 18, that is normally closed by means of the plug 19.

Operating within these bearings, are pistons 20 and 21, the piston 20 being provided with an opening in its lower end, through which the pipe 22 extends, the pipe 22 terminating at a point near the upper end of the piston, so that air 70 directed to the cylinder and piston, will be discharged against the upper end of the piston and against the oil within the piston.

The piston 21 has its lower end closed and is of the type commonly known as the full hydraulic 75 lift, or the type wherein fluid pressure against the bottom or lower end of the piston, operates to elevate the piston. The pipe 22 has connection with the pipe 23, which in turn is connected with the pipe 24, known as the supply pipe for the lift. 80

One end of the pipe 23 extends laterally, where it communicates with the cut out portion 12 of the cylinder 5. Air under pressure is directed to the pipe 24, through the pipe 25, the passage of the air through the pipes, being controlled by 85 means of the valves 26 and 27, the valve 27 controlling the passage of the air to the atmosphere, allowing the air to exhaust and the pistons to move to their initial or lowermost positions.

The upper end of the piston 20 is formed with 90 a filling opening, which is normally closed by the plug 28, whereby the piston 20 and cylinders may be filled with oil.

At the upper ends of the pistons, is an angle 95 bar 29 that connects the pistons and a part of the track structure of the lift, not shown.

Shoulders 30 are formed at the lower ends of the pistons 20 and 21 and are adapted to engage the lower ends of the bearings, thereby restricting vertical movement of the pistons, and 100 preventing the pistons from being forced out of the upper ends of the cylinders. A stop 16' is formed at the bottom of the cylinder 5 and restricts downward movement of the piston 20.

It will of course be understood that these 105 cylinders are embedded in the ground surface, so that the upper ends of the pistons operating within the cylinders, will be extended a slight distance above the ground surface. The cylinders are held in proper spaced relation with each other by 110

means of the bearing members 30' that are secured to the cylinders and arranged in spaced relation with each other.

In the use of the lift, an automobile is driven 5 onto the tracks of the lift, whereupon air under pressure is admitted to the piston 20, the air acting against the head of the piston and oil level in the cylinder.

Oil is forced into the cylinder 6, causing the 10 piston 21 thereof to be elevated, and since the pressure in both cylinders is equal, and because one piston relies on the movement of the adjacent piston, the pistons will move vertically in unison.

When it is desired to lower the lift, the valve 27 15 is operated to exhaust the air from the system, allowing the pistons to move downwardly and the oil to assume its normal level as shown in Figure 1 of the drawings.

Having thus described the invention, what is 20 claimed is:

1. An automobile lift comprising in combination, a pair of cylinders, pistons operating in the cylinders, said cylinders adapted to contain oil, a pipe establishing communication between the 25 cylinders, one of the pistons having an open bottom, an air pipe extending into the piston having the open bottom, the discharge end of the pipe being disposed above the oil level in the cylinders, and adapted to discharge air against 30 the head of the piston forcing the oil into the adjacent cylinder and elevating the pistons simultaneously.

2. An automobile lift comprising in combination, a pair of cylinders, pistons operating in the 35 cylinders, said cylinders adapted to contain oil, a pipe establishing communication between the cylinders whereby oil passes from one cylinder to the other cylinder, one of the pistons having an opening in its bottom, a pipe extending into 40 the open-ended piston and adapted to direct air under pressure to the space between the oil level in the piston and head of the piston, moving the piston upwardly and forcing the oil against the piston in the adjacent cylinder, elevating the 45 pistons simultaneously.

3. An automobile lift comprising in combination, a pair of communicating cylinders adapted to contain oil, pistons operating in the cylinders, one of the pistons having an opening in the bottom thereof allowing oil to enter the piston, a pipe extending into one of the pistons and adapt-

ed to discharge air at a point between the head of the piston and oil level in the cylinder forcing oil against the bottom of the adjacent piston, elevating the pistons, and means for controlling the supply of air to the pipe.

4. An automobile lift comprising in combination, a pair of communicating cylinders, pistons in the cylinders, said cylinders adapted to contain oil, pistons operating within the cylinders, said pistons being spaced appreciable distances from the walls of the cylinders providing oil spaces, one of the pistons having an opening in the bottom thereof permitting oil to pass into the piston, a pipe extending into the open-ended piston and adapted to direct air under pressure to the space between the head of the piston and oil level, forcing the oil in one cylinder against the piston of the adjacent cylinder elevating the pistons and means for controlling the passage of air under pressure to the cylinders.

5. An automobile lift comprising a pair of cylinders, lifting pistons operating within the cylinders, a pipe establishing communication between the cylinders, said cylinders containing oil, means for directing air under pressure to one 100 of the cylinders, thereby forcing oil from one cylinder against the piston of the adjacent cylinder, thereby elevating the pistons, and means for controlling the passage of air to the lift.

6. An automobile lift, comprising in combination, a pair of communicating cylinders adapted to contain oil, pistons movable in the cylinders, one of the cylinders constituting a reservoir for supplying oil to the adjacent cylinder, and means for directing air to the cylinder constituting the oil reservoir, lifting the piston contained therein and forcing the oil against the piston of the adjacent cylinder, simultaneously lifting the pistons.

7. An automobile lift comprising in combination, a pair of cylinders, said cylinders adapted to contain oil, pistons operating within the cylinders, an air pipe extending into one of the pistons and having the discharge end thereof disposed above the oil level, the piston in the opposite cylinder having its lowermost wall closed, means for directing air to the cylinders, and means for controlling the passage of air to the cylinders.

WILLIAM H. WARNER. 125

55. An automobile lift comprising a pair of communicating cylinders, pistons operating in the cylinders, one of the pistons having an opening in the bottom thereof allowing oil to enter the piston, a pipe extending into one of the pistons and adapt-

60. An automobile lift comprising a pair of communicating cylinders, pistons operating in the cylinders, one of the pistons having an opening in the bottom thereof allowing oil to enter the piston, a pipe extending into one of the pistons and adapt-
